UNITED STATES PATENT OFFICE.

WINFIELD E. HINSDALE, OF TRENTON, NEW JERSEY.

PIPE-CASING.

1,359,892.

Specification of Letters Patent. Patented Nov. 23, 1920.

Application filed March 1, 1920. Serial No. 362,187.

To all whom it may concern:

Be it known that I, WINFIELD E. HINSDALE, a citizen of the United States, residing at Trenton, in the county of Mercer and 5 State of New Jersey, have invented certain new and useful Improvements in Pipe-Casings, of which the following is a specification.

This invention pertains to an improved 10 pipe casing and has to do with such structures as are suitable for covering or incasing plumbing connections.

The invention is illustrated in conjunction 15 or relation to a closet tank and closet and in the drawings,--

Figure 1 is a side elevation of so much of a tank and closet as is necessary to an understanding of the present invention; and

Fig. 2 is a vertical sectional elevation of 20 the casing and the flushing pipe extending from the tank to the closet.

The object of the present invention is to provide a casing which may be extended as to length to accommodate itself to any installation or variation in length of the flushing pipe.

A further object is to so construct the casing that the same may be readily adjusted as to length, means being provided whereby the 30 sections of the casing are interlocked with each other to maintain them in such adjusted relation.

A still further object is to so construct the casing that no special fittings either upon 35 the tank or the casing to hold the casing in place are present or necessary, the absence of such fittings rendering the structure of universal application.

In the drawings, 1 denotes the closet, 2 40 the tank and 3 the flush pipe which is connected to said elements in any approved manner, as by couplings 4 and 5, respectively. The casing, which is generally formed of china or vitreous material, comprises two tube-like sections 6 and 7, the 45 lower section 6 being somewhat smaller in diameter than the upper one and preferably made slightly flaring or enlarged at its lower end. Said member 6 is provided at its upper end with a short externally located 50 male thread 8 which engages the internally formed thread 9 of the upper section 7. Said sections 6 and 7 are thus adjustably

interlocked and their length over all may be regulated and maintained as may be necessary or desirable. 55

When the closet and tank are being assembled the parts 6 and 7 will be screwed together so that their agreeable length will be at the minimum or substantially so. When 60 the flush pipe is secured in place in the bowl the casing will be slipped over the pipe, the upper end of the pipe remaining exposed so that the tank coupling 5 may be readily manipulated and secured in place. This being accomplished, the casing sections are turned with reference to each other, thread 8 being backed along thread 9 until the length of the casing is such that the lower end rests upon the top of the closet and the 70 upper end abuts the under face of the tank. Thus it will be seen that the flush pipe is entirely inclosed and that no connection is necessary between the casing and the tank to maintain the casing in place. Furthermore, should occasion require that access be had to either of the couplings 4 and 5, the 75 same may be effected by simply screwing the two casing sections together to shorten the over-all length of the casing, whereupon the 80 coupling 4 may be exposed by merely lifting the casing while coupling 5 will be exposed by allowing the then shortened casing to rest on the top of the closet.

As will be seen upon reference to Fig. 2, 85 the relatively short threaded portion of the lower section 6 will be housed by the upper member when the parts are assembled and as a consequence the casing presents a smooth exterior. 90

What is claimed is:

1. In combination with a closet; a tank; a flush pipe connecting said elements; and an extensible casing for said pipe, said casing comprising two elements adjustably secured to each other, the lower end of the casing resting upon the top of the closet and holding the upper end of the casing against the under face of the tank, said casing being free of any connection with the tank or the 100 fittings thereof.

2. In combination with a closet; a tank; a flush pipe connecting the same; and an extensible casing for the pipe, said casing comprising two sections of an internal diameter greater than that of the flush pipe, one 105

of said sections being internally threaded and the other of said sections having an externally threaded end adapted to engage the threads within the other section and to be hidden by the other member when the parts are assembled, whereby the casing may be adjusted to make close contact with the

upper face of the bowl and the under face of the tank and will present a smooth exterior surface.

In testimony whereof I have signed my name to this specification.

WINFIELD E. HINSDALE.
